[57] CLAIM

The ornamental design for a drill socket, as shown and described.

DESCRIPTION

FIG. 1 is a front and top-right perspective view of a drill socket showing my new design;

FIG. 2 is a front elevational view;

FIG. 3 is a top plan view;

FIG. 4 is a rear elevational view;

FIG. 5 is a right side elevational view;

FIG. 6 is a left side elevational view;

FIG. 7 is a front top-right perspective view of a second embodiment of my new design of FIGS. 1-6 the major difference being the length of the socket;

FIG. 8 is a front elevational view of FIG. 7;

FIG. 9 is a top plan view of FIG. 7;

FIG. 10 is a rear elevational view FIG. 7;

FIG. 11 is a right side elevational view of FIG. 7; and, FIG. 12 is a left side elevational view thereof.
